MACHINE FOR ASSEMBLING PAPERBOARD PARTITIONS

Heinz Ahlmeyer, Tappan, and Whitney D. Sherman, West Nyack, N. Y., assignors to Robert Gair Company, Inc., New York, N. Y., a corporation of Delaware

Application June 21, 1948, Serial No. 34,178

4 Claims. (Cl. 93—37)

1

The invention relates to mechanism for assembling crisscross partitions of paperboard and the like, such as the partitions used as separators in packing small articles, e. g. Christmas tree ornaments.

The crisscross partitions form individual cells of generally rectangular form, and conventionally are made by cutting parallel slits half-way across the partition cards so that, when assembled, a set of parallel partitions having the slotted edges up are crisscrossed by another set having the slotted edges down, the aligned opposed slots being brought into engagement to interlock the crisscross partitions with their respective upper and lower edges lying in common planes.

The usual practice in assembling the partitions has been to set them up by hand. This requires the employment of trained operators, is tedious work for employees, and is altogether a slow and expensive operation. However, to design a machine that would perform the same operation mechanically seemed to present quite a problem, because a most elaborate mechanism would be required in order to duplicate the manual procedure. Consequently, it has been an object of our invention to provide a mechanism for doing the job in a simpler and more expeditious way than would be the case if an attempt were made merely to mechanize the usual hand operation.

The hand operation essentially required assembling each unit individually, and it might be supposed that even with a machine running continuously it would be necessary to hold some of the partitions in a fixed position while others are crisscrossed with them in interlocking relationship. Thus we would have a machine having at least one fixed station, which would require a pause in the flow of work and impose a serious limitation on the productive capacity of the unit. However, we have found that the interrupted motions of such a machine, essentially reproducing the interrupted motions of hand assembly, can be eliminated, and that it is commercially practicable to have a continuously moving conveyor which advances a number of partitions in spaced parallel alignment, and to feed other partitions crisscross of the advancing partitions as they move past the feeding head. The first group of partitions advance in parallel ranks, and the other partitions, in single file, are brought into crisscross interlocking engagement, one at a time, with the first group while advancing continuously.

Another feature of our invention is that the mechanism arranges the first group of partitions

2

in alignment on a continuously moving transverse conveyor, from which they are transferred to a continuously moving longitudinal conveyor in sets without interrupting the movement of either conveyor. The transfer mechanism sweeps the set of partitions from one conveyor to the other in the split-second interval that the partitions on the transverse conveyor advance something less than the distance represented by the spacing between adjacent partitions. This avoids the requirement, which otherwise would exist, of interrupting the movement of the transverse conveyor.

Another feature is that we have been able to use a continuously moving transfer arm driven at uniform speed, properly timed for the aforementioned split-second sweeping action, while also properly timed for the interval required to accumulate a predetermined number of partitions on the transverse conveyor. This has been accomplished by mounting the transfer arm on a continuous chain the length of which is several times greater than the length of the partitions.

Another feature resides in the provision, on the transverse conveyor, of partition supporting slots which are inclined forwardly in respect of the direction of travel of the conveyor. We have discovered that this construction prevents the partitions from slipping out of the slots as they are received from the partition feeding head.

Other objects and advantages will appear as the description proceeds.

In the drawings:

Figs. 1a and 1b show, in side elevation, our preferred form of mechanism, Fig. 1a being cut off at the point where the crisscrossed partitions leave the second feeding head and enter the locking unit, and Fig. 1b showing the locking unit itself.

Figs. 2a and 2b show the same mechanism in plan view, with the feeding heads removed from Figs. 2a and replaced by a diagrammatic representation of these units.

Fig. 3 is a schematic perspective view illustrating the sequence of the operations of our mechanism as applied to assembling what is known as a "12-cell nest," consisting of nine crisscrossed partitions.

Fig. 4 is an enlarged vertical cross-sectional view of the first feeding head, taken as indicated at 4—4 in Fig. 1a, showing the parts in the position occupied at the conclusion of the operation of inserting a partition card P_1 in one of the slots 16.

Fig. 5 is a view similar to Fig. 4, showing the

parts in the position occupied at the beginning of the operation of inserting a partition card P_1 in one of the slots 16.

Fig. 6 is a detail horizontal cross-sectional view taken as indicated at 6-6 in Fig. 4.

Fig. 7 is a detail view showing a modified form of cam control for the second feeding head.

Fig. 8 is a diagram showing how partitions from the second feeding head are assembled with partitions advancing in spaced parallel alignment on a continuously moving conveyor as the advancing partitions move past the feeding head.

General arrangement

With reference to Figs. 1a and 1b, our mechanism comprises in its general arrangement a continuously moving longitudinal conveyor 10, a continuously moving transverse conveyor 11 adjacent thereto, a feeding head 12 adjacent the transverse conveyor for feeding partitions P_1 of paperboard or the like one at a time into spaced parallel arrangement on the transverse conveyor, transfer means 13 operative to transfer the partitions in sets from the transverse conveyor 11 to the longitudinal conveyor 10, while maintaining their spaced parallel arrangement, and a second feeding head 14 adjacent the path of travel of the partitions advancing in spaced parallel arrangement on the longitudinal conveyor for feeding other partitions P_2 one at a time into positions crisscross of said advancing partitions as they move past the second feeding head.

The transverse conveyor 11 has supports 15 for holding partitions in spaced parallel arrangement, these supports comprising slots 16 (Fig. 4) to receive the partitions P_1 , these slots being inclined forwardly in respect of the direction of travel of the conveyor. The transfer means 13 comprises a transfer member, arm 17, arranged to intermittently reverse the conveyor 11 in a direction normal to the direction of travel of the conveyor, to sweep the partitions from the slots in sets. This intermittent traversing action is so timed that the transfer arm 17 will clear the conveyor within the space of time that the conveyor advances a distance equal to the distance between adjacent slots 16. The transfer arm 17 is carried by a continuous chain or pair of chains 18, the length of which is several times greater than the length of the partitions, so that the transfer arm traverses the transverse conveyor at intervals spaced to allow accumulation of a predetermined number of partitions on the transverse conveyor, while the chains are driven at a substantially constant speed sufficient to cause the transfer arm to clear the conveyor within the space of time stated.

The timing of the operation of the transfer arm in relation to the timing of the transverse conveyor is important. Specifically, the lineal velocity of the transfer arm 17 is at least equal to

$$\frac{l}{d} \times \text{the velocity}$$

of the transverse conveyor 11 where d is the distance between the spaced parallel partitions and l is the length of the partitions.

Also, the timing of the traversing action of the transfer arm 17 in relation to the timing of the transverse conveyor 11 is important. This is determined with relation to the factors above stated, and additionally with relation to the

length of the chains 18 which carry the transfer arm. Specifically, the length of these chains is

$$v_2 \times \frac{nd}{v_1}$$

where n is the predetermined number of partitions P_1 and v_1 and v_2 are the respective velocities of the transverse conveyor and chain.

A cut-out control 19 is provided on the second feeding head 14, whereby its operation can be interrupted during the intervals between the time that one set of partitions from the feeding head has left the second feeding head and the time that the succeeding set of partitions enters the second feeding head.

Referring to Figs. 1b and 2b, we have shown a locking unit 24, the function of which is to press the crisscrossed partitions into their final interlocked relationship by means of a pressing member 20 having a shouldered bearing surface 21, 22. The pressing member reciprocates in a manner to bring first one part 21 and then the other part 22 of the shouldered bearing surface into engagement with the upper edge of each crisscross partition in turn to press them into interlocking engagement in two steps.

The foregoing comprise the essential components of our mechanism. The related structure, comprising the framework of the machine, the driving mechanism, including variable speed control switches and the like, may assume various forms without departing from our invention. In the particular embodiment illustrated, the conveyor units 10, 11, feeding heads 12, 14, and transfer means 13, together with their associated driving and timing mechanism, are mounted on a frame indicated generally at 23 (Fig. 1a). The locking unit 24 with its associated driving and timing mechanism is mounted on a second frame unit 25 (Fig. 1b) which may if desired be formed as an extension of the frame 23.

The feeding heads

Feeding heads 12 and 14 may be of similar construction, so it will suffice to describe one of them. Its function is to feed partitions one at a time, i. e. in single file, as distinguished from movement of the spaced parallel partitions in sets or parallel ranks. In our preferred mechanism, the feeding head 12 takes the form illustrated in Figs. 1a, 4 and 6. It comprises a pair of supporting columns 26 mounted on the frame 23, between which extends at their upper ends a cross bar 27 and at their lower ends a friction guide plate 28 positioned just above the supports 15 of the transverse conveyor 11. A hopper 29 for the partitions P_1 is fixed to the feeding head, being supported by frame members 30, 31 as shown. The bottom 32 of the hopper extends between supports 26, and is inclined as shown in Fig. 4. The sides of the hopper are formed by adjustable guides 33 which may conveniently be made of angle irons with one flange extending vertically and the other flange extending in parallelism with the bottom 32 for attachment thereto. The spacing of the guides 33 is adjusted in accordance with the length of the partition cards to be handled. Upper guides 34 are fixed to the frame of the feeding head as by means of brackets 35 and a cross bar 36 to which the brackets are secured and which are in turn mounted on the vertical supports 26. These upper guides are arranged in line with the top edges of the partitions P_1 . At its lower end the bottom 32 of the hopper is flush with the for-

70

ward (right-hand as viewed in Fig. 4) surface 38 of the guide plate 28. Guides 33 at their lower ends are formed with inwardly extending vertical flanges 37 against which bear the ends of the leading partition card in the hopper. The rearward surface of flanges 37 is disposed ahead of the forward surface 38 of guide plate 28 by an amount which closely approximates the thickness of the partition cards. This is referred to as the "metering gap" of the feeding head.

The guiding of the cards as they are fed from the hopper to the transverse conveyor is further assisted by means of a friction guide finger 39 disposed at or near the center of the hopper (Figs. 4 and 6), and against or in close proximity to the reciprocating plate 40. This guide finger, like the flanges 37, is disposed with its rearward surface just slightly in advance of the forward surface 38 of friction guide plate 28. Guide finger 39 preferably is made of spring steel to make it somewhat resilient, and besides guiding the cards as they are pushed down into the slots of the transverse conveyor, prevents them from dropping out of the hopper until they are pushed downwardly by the feeding mechanism which now will be described.

Plate 40 is mounted for vertical reciprocation in the guide channels 41 at the sides of the feeding head, adjacent the discharge end of the hopper. The reciprocatory movement of the plate is imparted by a crank 42 with a connecting rod 43 pivotally secured to the crank and to the plate 40, as shown. Crank 42 has an adjustable slide 44 to which the connecting arm 43 is pivotally secured to make it possible to adjust the length of the crank arm and accordingly the length of the operating stroke of the plate 40. The length of connecting rod 43 also is made adjustable, as by means of the double-ended screw 45. The adjustable slide 44 and screw 45 are designed to permit the accommodation of partition cards of different heights. Crank 42 is mounted in suitable bearings on the frame and driven by means of a chain 46 from the common drive shaft 48 to which reference has been made.

Reciprocating plate 40 carries a pair of pusher fingers 147, the lower ends of which are notched out at 148 to receive the upper edges of the partition cards. The transverse depth of these notches is equal, or very closely so, to the caliper of the paperboard from which the partitions P_1 are made. Pusher fingers 147 are adjustable both laterally and vertically by means of securing bolts 149 which are received in selected holes of the series 150, and in holes 154 of the fingers (Fig. 1a). Pusher fingers 147 are adjusted vertically so that when they are in the fully retracted position shown in Fig. 5 the base of notches 148 is just slightly above the tops of the partition cards—say about $\frac{1}{2}$ in. The length of the stroke of the pusher finger is adjusted so that in their fully advanced position shown in Fig. 4, the partition card will have been brought snugly into the bottom of one of the slots 16 of the transverse conveyor.

Also mounted on the reciprocating plate 40 are a pair of brackets 151. If desired, these brackets can be secured to the plate by the same bolts which hold the pusher fingers 147, as shown. The lower ends 152 of brackets 151 preferably are disposed at an angle to the horizontal which corresponds to the inclination of the bottom 32 of the hopper, so that when they are in their

fully advanced position shown in Fig. 4, they will lie against the tops of the partition cards and compress them slightly. The purpose of these brackets is to snug the cards into position at the lower end of the hopper so that upon the return stroke of the pusher fingers 147, the cards will snap into engagement with the notches thereof.

Slots 16 of supports 15 of the transverse conveyor 11 are flared outwardly at their entrances to assist in guiding the partitions P_1 into the slots as they are pushed downwardly by the fingers 147. With reference to Fig. 4, it will be observed that when a partition is inserted into one of the slots 16, its lower edge is constrained, being deflected rearwardly in respect of the direction of movement of the conveyor. When, on the return stroke of the feeding mechanism, fingers 147 are released from the upper edge of the card, it snaps forwardly as shown in Fig. 5. We have found that the inclined slots are very important in preventing the partitions from jumping out of the slots of the conveyor when the machine is operated at high speed.

As previously stated, the second feeding head 14 may be of the same construction as feeding head 12 just described. However, in order to permit partitions P_1 advancing on conveyor 10 to pass through the second feeding head, the friction guide plate 28' which corresponds to guide plate 28 of Figs. 4 and 5 is notched out at its lower edge sufficiently to allow clearance for these partitions, as indicated at 153.

The operation of reciprocating plate 40 of feeding head 12 is synchronized with the operation of the continuously moving transverse conveyor 11, transfer arm 17, continuously moving longitudinal conveyor 10, and reciprocating plate 40 of the second feeding head 14, through a common drive which may comprise motor 45, variable speed control 46, speed reducer 47, and main drive shaft 48, with associated driving mechanism as shown in the drawings.

The transverse conveyor

The transverse conveyor 11 (Fig. 4) comprises supports 15 for holding the partitions in spaced parallel arrangement, these supports being fixed to a pair of continuous chains 49, 49. As has been noted, supports 15 comprise slots 16 for holding the partitions. These slots are inclined forwardly in respect of the direction of travel of the transverse conveyor, a construction which prevents the partitions from jumping out of the slots as they are received from the feeding head 12.

After a predetermined number of partitions has been accumulated in spaced parallel alignment on the transverse conveyor 11 in line with the longitudinal conveyor 10, the transfer arm 17 sweeps the accumulated partitions from the slots 16 of transverse conveyor 11 and places them on the continuously moving conveyor 10.

The transfer mechanism

The transfer mechanism will now be described with reference to Figs. 1a and 2a. It comprises transfer arm 17 mounted on a pair of chains 18, this transfer arm being in line with the longitudinal conveying means 19. An important feature of the transfer means is that the transfer arm 17 traverses the transverse conveyor 11 so as to clear the accumulated set of partitions from the slots 16 within the space of time that conveyor 11 advances a distance equal to the

distance between slots 16. Another feature is the use of a continuously moving transfer arm 17 driven at uniform speed, properly timed for the aforementioned traversing action, and also properly timed for the interval required to accumulate a predetermined number of partitions on the transverse conveyor 11. This has been accomplished by making the length of chains 18 several times greater than the length of the partitions.

More specifically, the timing of the velocity of the traversing action of the transfer arm 17 and the length of the chains 18 is as follows:

Velocity of the transfer arm 17 is at least equal to

$$\frac{l}{d} \times \text{velocity}$$

of conveyor 11, and

$$\text{Length of chains 18} = v_2 \times \frac{nd}{v_1}$$

where

d is the distance between the spaced parallel partitions (i. e. the distance between slots 16)

l is the length of the partitions

n is the predetermined number of partitions P_1 (i. e. the number of partitions in a set)

v_1 is the velocity of conveyor 11

v_2 is the velocity of transfer arm 17.

In applying these formulae, it will be found that chain 18 will be quite long, and the length of chain can be handled most conveniently by having it follow a circuitous path as is clearly shown in Fig. 1a. The direction of travel is as indicated by the arrows on the drawing. The lower branch of the chains as they cross above the transverse conveyor 11 is just slightly above the conveyor's surface so that arm 17 engages the ends of the partitions, sweeping them from left to right as seen in this view. This action is illustrated diagrammatically in Fig. 3, where the predetermined number of partitions has been accumulated on conveyor 11 at *b* and is swept toward position *c* by the transfer arm.

The longitudinal conveyor

Just before the partitions reach position *c*, they are picked up by the longitudinal conveyor means indicated diagrammatically at 10. This conveying means will now be described with reference to Figs. 1a and 2a. In our preferred construction, this comprises a continuous pair of chains 50, 50 carrying bars 51 uniformly spaced in accordance with the length of the partitions and timing of the transfer arm 17 relative to the movement of conveyor 10. This conveyor also comprises means for guiding the partitions and for adjusting the spacing thereof as they are brought to the second feeding head 14. In the embodiment illustrated, the partitions slide across a fixed table 52. To this table are affixed a series of guides 53 whose entering portions are widened, as at 54, for ease of transfer of the partitions from the moving transverse conveyor 11, and to allow the partitions to be brought into vertical position from their inclined position in slots 16. At 55, guides 53 fan outwardly to meet the parallel guide sections 56 which hold the partitions in proper spaced relationship corresponding to the spacing of the slots 57 (Fig. 8) of partitions P_2 which are to be interlocked therewith at the second feeding head 14.

The cut-out control

The second feeding head 14 is like the first feeding head 12 already described, and its operation is the same except that a cut-out control is provided on the second feeding head whereby its operation can be interrupted during the interval between the time that one set of partitions from the first feeding head has left the second feeding head and the time that the succeeding set of partitions enters the second feeding head. The purpose of the cut-out is to stop the feeding of cards from the second feeding head over the blank spaces of the longitudinal conveyor. The cut-out control may comprise a conventional single revolution clutch and brake well known in the machinery art, and its operation is controlled by a suitable cam driven from a shaft of the conveyor chains 50. This cam is indicated at 155 in Fig. 1a, which also shows diagrammatically the single revolution clutch and brake.

It will be appreciated that interrupted feeding at the second feeding head is necessary only where there is a space between the advancing ranks of parallel partitions P_1 on conveyor 10. In a machine designed for one particular size of partition, there need be no space between the advancing ranks, and if the distance between the trailing slot of one rank of partitions and the leading slot of the succeeding rank of partitions is equal to the distance between slots, it will be understood that there need be no interruption of the operation of the second feeding head. In this case, the cam 155 previously referred to may be replaced by a cam 156 indicated in Fig. 7, so that the operation of the second feeding head will be continuous; or if desired, the cut-out control comprising the cam and the single revolution clutch and brake can be omitted entirely, with simple coordination of the operation of the second feeding head and the conveyor by connection to the common drive. However, we prefer to have a cut-out control so that the machine is adaptable to handling different sizes of partitions. Thus the mechanism here shown is of more universal application.

Operation of second feeding head

As the set of advancing partitions P_1 move past the feeding head 14, partitions P_2 (e. Fig. 3) are fed crisscross of the advancing partitions *d*. Partitions P_2 are interlocked with partitions P_1 without interrupting the continuous movement of partitions P_1 through the machine. The action of interlocking the crisscross partitions during forward movement of partitions P_1 is illustrated diagrammatically in Fig. 8, succeeding relative positions of partitions P_1 and P_2 being illustrated, reading from top to bottom. Advantage is taken of the beveled entering portions 58 of slots 57 of partitions P_1 and P_2 (the slots of partitions P_1 and P_2 usually are of identical form) during this operation. In the second position from the top of Fig. 8, it will be observed that partitions P_1 and P_2 have begun to overlap prior to the time that their respective slots 57 are in alignment. In the third position, the beveled entry portion 58 of partition P_1 affords clearance just prior to the time when the partition P_1 is in exact alignment with the descending partition P_2 . When the lowermost position is reached, slot 57 of partition P_1 is exactly opposite the feeding head or only slightly advanced therefrom.

The locking unit

The nest of crisscross partitions has now been completed except for locking them in their final position. It will be observed that as the nest leaves the second feeding head (d, Fig. 3), the upper edges of partitions P_2 are above the plane of the upper edges of partitions P_1 . At this point the respective bases 59 of the slots 57 of partitions P_1 and P_2 are resting lightly in engagement. Slots 57 have a narrow extension in the form of a cut 60, and when the edges of partitions P_1 and P_2 are brought into the same plane, there is an overlapping of the cuts 60 of the respective partitions, which locks them together.

Final alignment of the partitions is accomplished by the mechanism illustrated in Fig. 2b and shown diagrammatically at f in Fig. 3. It comprises the pressing member 20 having the shouldered bearing surface 21, 22 and which reciprocates vertically to bring first one part and then the other part of the shouldered bearing surface into engagement with the upper edges of each crisscross partition P_2 in turn to press them into interlocking engagement with partitions P_1 at the cut lines 60. The nests are carried under the pressing member 20 by means of a suitable conveyor 61 which picks up the nests as they are discharged from conveyor 18 at 62 (Fig. 1a). Conveyor 61 may be a simple belt conveyor as shown, and there may be suitable guides 63 to keep the partitions in proper position as they advance toward the pressing member 20. The shoulder 21 of pressing member 20 may be so spaced with reference to shoulder 22 that when the pressing member is in its lowermost position, partitions P_1 and P_2 will be accurately aligned with the bases of their respective slots 57 in engagement. After this alignment has been secured, the final locking action is performed by shoulder 22 which brings the cuts 60 of the respective partitions into interlocking engagement, with the upper and lower edges of the partitions in common planes.

Conveyor 61 is driven in any suitable manner as by means of motor 64, speed reducer 65, variable speed control 66, and associated driving mechanism as shown. The speed of conveyor 61 preferably is adjusted to keep the spacing between successive nests to a minimum, thus increasing to the maximum the number of blows of the pressing member on each nest.

The apparatus we have described, when set up as illustrated in Figs. 1a and 2a, is designed to assemble 100-cell nests consisting of twenty-two partitions (11 x 11), up to 12 in. long, spaced $\frac{1}{2}$ in. apart. Assuming a velocity of 10 ft. per minute for conveyor 11, with partitions 12 in. long, the velocity of transfer member 17 will be at least equal to

$$\frac{10}{12} \times 10 (= 200 \text{ ft. per minute})$$

$$\frac{0.5}{12}$$

for example 220 ft. per minute. The length of chains 18 will then be

$$220 \times \frac{11 \times 0.5}{12}$$

or 10.1 ft.

Other sizes and shapes of nests can be assembled, e. g. the 12-cell, 4 x 5 nests of nine partitions indicated in Fig. 3.

The terms and expressions which we have employed are used in a descriptive and not a limiting sense, and we have no intention of excluding such equivalents of the invention described, or of portions thereof, as fall within the purview of the claims.

We claim:

1. In mechanism for assembling criss-cross partitions of paperboard and the like, a continuously moving longitudinal conveyor, a continuously moving transverse conveyor having supports for holding partitions in spaced parallel arrangement, a feeding head adjacent the transverse conveyor for feeding partitions into spaced parallel arrangement in said supports, a transfer member intermittently traversing the transverse conveyor in a direction normal to the direction of travel of the transverse conveyor to transfer the partitions in sets from the transverse conveyor to the longitudinal conveyor, a mechanical drive for said transverse conveyor arranged for operation at a predetermined constant speed, and a mechanical drive for said transfer member arranged for operation at a predetermined constant speed, said mechanical drives being interlocked for maintenance of a constant speed ratio therebetween, the mechanical drive for said transfer member consisting of a continuous chain and said transfer member consisting of an arm carried by said chain, the length of said chain being several times greater than the length of the partitions so that said arm traverses the transverse conveyor at intervals spaced to allow accumulation of a predetermined number of partitions on the transverse conveyor while the chain is driven at a substantially constant speed sufficient to cause said arm to clear the transverse conveyor within the space of time that said conveyor advances a distance equal to the distance between the spaced parallel partitions.

2. In mechanism for assembling crisscross partitions of paperboard and the like, a continuously moving longitudinal conveyor, a continuously moving transverse conveyor having supports for holding partitions in spaced parallel arrangement, a feeding head adjacent the transverse conveyor for feeding partitions into spaced parallel arrangement in said supports, a transfer member intermittently traversing the transverse conveyor in a direction normal to the direction of travel of the transverse conveyor to transfer the partitions in sets from the transverse conveyor to the longitudinal conveyor, a mechanical drive for said transverse conveyor arranged for operation at a predetermined constant speed, and a mechanical drive for said transfer member arranged for operation at a predetermined constant speed, said mechanical drives being interlocked for maintenance of a constant speed ratio therebetween such that the transfer member will clear the transverse conveyor within the space of time that the transverse conveyor advances a distance equal to the distance between the spaced parallel partitions, the lineal velocity of the transfer member being at least equal to l/d times the velocity of the transverse conveyor where d is the distance between the spaced parallel partitions and l is the length of the partitions.

3. In mechanism for assembling crisscross partitions of paperboard and the like, a continuously moving longitudinal conveyor, a continuously moving transverse conveyor having supports for holding partitions in spaced parallel arrangement, a feeding head adjacent the transverse conveyor for feeding partitions into spaced parallel

lel arrangement in said supports, a transfer member intermittently traversing the transverse conveyor in a direction normal to the direction of travel of the transverse conveyor to transfer the partitions in sets from the transverse conveyor to the longitudinal conveyor, a mechanical drive for said transverse conveyor arranged for operation at a predetermined constant speed, and a mechanical drive for said transfer member arranged for operation at a predetermined constant speed, said mechanical drives being interlocked for maintenance of a constant speed ratio therebetween such that the transfer member will clear the transverse conveyor within the space of time that the transverse conveyor advances a distance equal to the distance between the spaced parallel partitions, the lineal velocity of the transfer member being at least equal to l/d times the velocity of the transverse conveyor where d is the distance between the spaced parallel partitions and l is the length of the partitions, and the length of the chain being

$$v_2 \text{ times } \frac{nd}{v_1}$$

where n is the predetermined number of partitions, and v_1 and v_2 are the respective velocities of the transverse conveyor and chain.

4. In mechanism for assembling crisscross partitions of paperboard and the like, a continuously moving longitudinal conveyor, a transverse conveyor mechanism disposed adjacent the longitudi-

dinal conveyor for arranging partitions in spaced parallel arrangement opposite the end of the longitudinal conveyor and parallel to the direction of travel of the longitudinal conveyor, transfer means operative to place the partitions on the continuously moving longitudinal conveyor, a feeding mechanism disposed adjacent the path of travel of the partitions advancing in spaced parallel arrangement on the longitudinal conveyor for feeding other partitions one at a time into positions crisscross of said advancing partitions as they move past said feeding mechanism, a pressing member having a shouldered bearing surface, the crisscross partitions leaving the feeding mechanism passing under said pressing member which reciprocates in a manner to bring first one part and then the other part of said shouldered bearing surface into engagement with the upper edges of each crisscross partition in turn to press them into interlocking engagement with said advancing partitions in two steps.
